UNITED STATES PATENT OFFICE.

JOHN PEARCE ROE, DECEASED, LATE OF LONDON, ENGLAND, BY LUCY JANE ROE,
EXECUTRIX, OF LONDON, ENGLAND.

CARRIER HAVING GRIPPING DEVICE FOR USE WITH AERIAL ROPEWAYS.

Application filed May 31, 1922. Serial No. 564,944.

To all whom it may concern:

Be it known that I, LUCY JANE ROE, executrix of JOHN PEARCE Roe, deceased, a subject of the King of Great Britain and 5 Ireland, residing at 6 Thyra Grove Finchley, London, N. 12, England, represent that JOHN PEARCE Roe is the inventor of certain Improvements in or Relating to Carriers Having Gripping Devices for Use with 10 Aerial Ropeways, of which the following is a specification.

This invention has reference to that type 15 of load carrier suitable for supporting and transporting pendant loads on aerial ropeways of the mono-cable type, wherein the carrier is provided with gripping mechanism, comprising gripping levers so mounted or articulated upon a fulcrum pin within the carrier frame, that when the carrier with 20 its load is applied to and supported by the said rope, the weight of the load, acting vertically through the carrier will cause the gripping levers to close upon and then grip the rope, and conversely, the gripping levers 25 will be released and allowed to move into their open position when the weight of the carrier with its load is removed from the rope and taken by a shunt rail or equivalent device by means of the wheels of the 30 carrier engaging therewith.

In such a carrier the gripping levers have commonly been adapted to be moved into their closed and operative position upon downward movement of the carrier relatively to the fulcrum pin, by toggles arranged 35 between the upper end portions of the levers and the body of the carrier, downward movement of the levers, when the carrier is moved upward relatively to the fulcrum 40 pin, being limited by stirrup shaped stops on the carrier into which pins on the levers extend. In a modified arrangement, the upper ends of the gripping levers, provided 45 with antifriction rollers, work in two separate oppositely inclined grooves formed in the carrier, the arrangement being such that when the carrier takes the load, the sides of the grooves act to move the levers into their closed and operative positions, downward movement of the levers, when the carrier 50 is moved upward relatively to the fulcrum pin, being limited by pins on the upper ends of the levers abutting against the lower ends of slots formed in the end walls 55 of the grooves.

The present invention has for its object to improve the construction and working of load carriers of the type referred to.

For this purpose in a load carrier constructed according thereto, the gripping levers are moved into their close and operative position to grip an aerial rope by anti-friction roller operating means mounted on the carrier so as to move vertically therewith and arranged to act against oppositely inclined surfaces on the inner or outer edges of the levers when the carrier takes the load and are positively moved into their open and inoperative positions to release the rope by opening means arranged to act against other parts of the levers when the carrier is lifted relatively to the fulcrum pin by a shunt rail or equivalent, such opening means serving also to support the levers vertically when detached from the rope. The lever opening means may conveniently be constituted by abutment devices arranged on the carrier so as to abut against the levers when the carrier is lifted relatively thereto. Or the lever opening means may be constituted by a spring device carried by the levers and adapted to open the levers, when they are relieved of the weight of the carrier and cause them to become engaged with supporting means on the carrier, as for example with the roller operating means therein.

The formation of the inclined surfaces on the levers is such as to obviate the varying grip on the rope, resulting from toggles or the like heretofore used, the leverage of which varies with changing angles, and in place whereof, secures a predetermined amount of pinch or grip of the levers which remains practically constant throughout the gripping range of the mechanism and also provides for a rapid opening and closing movement of the levers outside the gripping range, the inclined surfaces being suitably shaped to bring about this effect.

The inclined surfaces on the gripping levers and the antifriction roller operating means for co-acting therewith and the abutment means, when used, may be arranged above or below the fulcrum pin on which the levers are mounted.

The gripping levers in addition to being able to move vertically in relation to the carrier, are also so mounted in the carrier that they can oscillate in a vertical plane corre-

sponding to the longitudinal direction of the moving rope with which the carrier is used, so as to adjust themselves to any vertical angle or curvature imparted to the rope 5 at or near the gripping point or points and thus avoid the objectionable stresses resulting from gripping devices that do not adjust themselves to rope angularity or curvature when passing for example over supporting sheaves.

The accompanying illustrative drawings show various constructions of carriers with gripping mechanism of the kind hereinbefore referred to. In these drawings, Fig. 1 15 shows partly in side elevation and partly in longitudinal section and Fig. 2 in plan, one such construction. Figs. 3 and 4 are cross sections thereof on the line III—III of Fig. 1, the gripping devices being shown in 20 their closed position in Fig. 3 and in their open position in Fig. 4. Fig. 5 is a diagrammatic view showing the effect of increasing the diameter of rollers to compensate for wear or to adapt the mechanism for 25 ropes of different sizes. Figs. 6 and 7 are similar views to Figs. 3 and 4 respectively, showing a modified construction. Figs. 8, 8 and 10 show another construction, Figs. 9 30 and 9 being cross sections with the gripping devices in their closed and open positions respectively and Fig. 10 shows the gripping devices in side view. Figs. 11, 12 and 13 are similar views to Figs. 8, 9 and 10 respectively, showing another construction. 35 Figs. 14, 15 and 16 are also similar views to Figs. 8, 9 and 10 respectively, showing another modified construction, Fig. 16 also showing part of the carrier frame in side elevation. Fig. 17 shows in plan, Fig. 18 in 40 cross section on the line XVIII—XVIII of Fig. 17, and Fig. 19 in section on the line XIX—XIX of Fig. 18, a further modified construction. Fig. 20 shows in plan, a modified arrangement.

In each example, *a* is the carrier frame with hollow extensions *b* to receive the upper end of a hanger to support the load to be carried; *c* are wheels journaled in the carrier and adapted to be engaged with a shunt rail *d*, or its equivalent, such as an endless secondary moving rope or track, when the carrier with its load is to be removed from an aerial rope *e*. *f*, *f*, are two upwardly extending arms and *f*¹ a downwardly extending arm with jaw *f*² constituting one of the gripping levers *F*, and *g* is the upwardly extending arm and *g*¹ the downwardly extending arm with jaw *g*² constituting the second gripping lever *G*, the 50 arm *g*¹ being arranged between the arms *f*¹, and *h* is a fulcrum pin upon which the two levers are mounted.

In Figs. 1 to 5 inclusive, the two gripping levers *F* and *G* with their fulcrum pin *h* 65 are loose and free to move vertically in a

box *a*¹ forming part of the carrier frame *a*. The inner adjacent surfaces of the upper portions of the lever arms *f* and *g* are inclined, as shown at *f*³ and *g*³ respectively to form a vertical space *i* between them to receive co-axial rollers *k* when the gripping levers are moved into their closed positions, as shown in Fig. 4, and are inclined outwardly and upwardly as shown at *f*⁴ and *g*⁴ respectively to admit of their passing 70 below the rollers *k* when the gripping levers are in their open positions, as shown in Fig. 4. The surfaces *f*³ *g*³ are arranged to form a slightly acute angle with one another, whilst the surfaces *f*⁴ *g*⁴ form an obtuse 75 angle to one another, when the gripping levers are in the closed and operative position shown in Figs. 3 and 5. At their outer edges, the levers *F* and *G* are formed with curved surfaces *f*⁵ and *g*⁵ respectively adapted to co-act with companion cam or abutment devices *m* and *n* provided on the inner side of the box *a*¹. The cam device *m* may be integral with such box whilst the cam device *n* is detachable therefrom to admit of 80 the gripping levers with their fulcrum pin *h* being inserted in the box. The rollers *k* are carried by a spindle *o* capable of movement, in a longitudinal direction, in bearings in the box *a*¹. The opposite outer sides 85 of the lever *F* are provided with extensions *f*⁶ that act as guiding devices for the gripping mechanism within the box *a*¹ without preventing oscillation of such gripping mechanism in the longitudinal direction. *f*⁷ 90 and *g*⁷ are lateral projections on the outer sides of the gripping levers to limit lateral movement of the levers when in their open position (Fig. 4).

As will be seen, with the arrangement described, when the carrier with gripping mechanism and load is applied to an aerial rope *e*, the lower arms of the gripping levers will bear on the rope and the weight of the carrier and load will be transmitted 105 through the rollers *k* to the inclined surfaces *f*⁴, *g*⁴ and *f*² and *g*² of the levers *F* and move these arms apart from the position shown in Fig. 4 to that shown in Fig. 3, so as to cause the jaws on the levers to grip the rope 110 *e* between them, with a force dependent upon the weight of the carrier frame and load, and of the angle of inclination at the surfaces *f*³ *g*³. When the carrier is run on to a shunt rail *d* so as to detach it from the 115 rope *e* and lift it relatively to the rope *e*, the gripping devices will fall and come into contact with the fixed cam devices *m* and *n* which, acting on the companion surfaces *f*⁵ and *g*⁵, will cause the falling levers to 120 move into the open position (Fig. 4). To allow for small variations in diameter of 125 ropes to which the carrier is applied, and also to compensate for wear of the rope, the surfaces *f*³, *g*³ of the levers are slightly in- 130

clined to one another in the downward direction and made sufficiently long, as shown in Fig. 5, to permit the rollers k to act against them until the jaws of the levers 5 grip the rope. To provide for greater wear, rollers k of larger diameter can be used, as indicated by a dotted circle at k^* in Fig. 5. In Figs. 6 and 7 the cam devices to co-act with the cam surfaces f^5 , g^5 of the 10 gripping levers are constituted by endways adjustable screws m^1 , n^1 .

In Figs. 8, 9 and 10, the upper ends of the gripping levers are connected by a coiled spring r and are made of concave 15 shape as shown at f^8 , g^8 so that when the carrier is raised relatively to the rope e by a shunt rail d , the levers will be positively moved into their open and inoperative positions by the spring and their upper curved 20 ends caused to embrace the rollers k so that they will then be supported thereby in their open positions.

In Figs. 11, 12 and 13 the fulcrum pin h is arranged near the upper extremities of 25 the levers F and G , and the surfaces f^3 , g^3 and co-acting rollers k , are between the fulcrum h and the gripping jaws f^2 , g^2 . In this case, the levers are shaped and arranged, as shown, so that their lower portions 30 cross one another to admit of the weight of the carrier and its load, acting through the rollers k , forcing the jaws f^2 , g^2 towards one another to grip the rope e (Fig. 11). The upper arms f and g of the 35 levers are bent outward to co-act with the top of the side walls of the box a^1 which act as abutment devices to move the levers into their open position when the carrier with its load becomes detached from the rope by 40 the shunt rail d (Fig. 12).

In Figs. 14, 15 and 16, the gripping levers F and G are jointed to a fulcrum pin h arranged near their upper ends and the jaws f^2 , g^2 are caused to grip the rope e , under 45 the action of the weight of the carrier and load, by rollers k^1 , k^2 connected to the carrier and acting against cam surfaces f^3 , g^3 formed on the outer sides of the levers between the fulcrum pin and jaws. In this 50 example the levers are mounted in a secondary box-like part a^4 pivoted at a^5 to the part a^1 to admit of the gripping mechanism readily oscillating in a direction parallel to the longitudinal direction 55 of the rope e and in relation to the carrier frame of which the box a^1 forms part. The rollers k^1 are journalled in the part a^4 and the upper arms f and g co-act with the upper ends of the said part a^4 as 60 shown in Fig. 15, to open the jaws f^2 , g^2 when the carrier with its load is lifted off the rope e .

In the arrangements shown in Figs. 11, 12, 13 and Figs. 14, 15 and 16, the fulcrum 65 pin h extends into vertical slots, one of

which is shown at a^6 , formed in the end walls of the box like part a^1 , or secondary box like part a^4 .

In Figs. 17, 18 and 19 the fulcrum pin h carrying the gripping levers F and G is 70 mounted in bearings a^7 carried by the lower portion of a secondary box-like part a^8 adapted to move vertically on the box-like part a^1 of the carrier a to which it is loosely jointed by a transverse pin f^* mounted in 75 the carrier and extending through vertical slots a^9 in the said box-like part a^8 . The arrangement is such as to admit of the gripping levers readily oscillating in the longitudinal direction of the rope with 80 which they are engaged, under conditions such as hereinbefore mentioned. k are the rollers mounted on the pin o supported by the carrier b and adapted to close the levers and cause them to grip a movable rope as 85 in the other arrangements. m^2 and n^2 are transverse pins carried by the box-like part a^1 and adapted to act as abutment devices for positively moving the gripping levers into their open position when the carrier b 90 is raised relatively to the rope with which it is used. In this example, the carrier comprises two main longitudinal members $a-a$ connected by spindles u upon the central position of which sheaves c are mounted, 95 one of the said members a carrying the box-like part a^1 to which the outer box-like part a^8 is loosely connected as described.

In the arrangement shown in Figs. 1 and 2 the carrier frame a is provided with gripping mechanism at one end only and is provided at its other end with a saddle piece s that merely rests on the rope e without performing any material gripping action thereon. Fig. 20 shows an arrangement in which 105 each end of the carrier frame a is provided with gripping mechanism that may be constructed and arranged in any of the ways hereinbefore described but is shown like that illustrated in Figs. 1 to 4. 110

What I claim is:—

1. In a load carrier of the type herein referred to for an aerial ropeway, rope gripping mechanism comprising a pair of gripping levers the lower ends of which are 115 adapted to grip an aerial rope between them and edge portions of which above said lower ends are formed with oppositely inclined edge surfaces, a fulcrum pin for said levers free to move in a vertical direction relatively to the carrier, means on said carrier adapted, on downward movement thereof relatively to said fulcrum pin to act against the opposite inclined surfaces on the levers and cause the levers to grip a rope, and 120 means adapted, upon upward movement of said carrier relatively to said fulcrum pin to cause the levers to become disengaged from the rope.

2. In a load carrier of the type herein re- 130

ferred to for an aerial ropeway, rope gripping mechanism comprising a pair of gripping levers, the lower ends of which are adapted to grip an aerial rope between them and edge portions of which above said lower ends are formed with oppositely inclined edge surfaces, a fulcrum pin for said levers free to move in a vertical direction relatively to the carrier, an antifriction roller, 5 on said carrier adapted, on downward movement thereof relatively to said fulcrum pin to act against the opposite inclined surfaces on the levers and cause the levers to grip a rope, and means adapted, upon upward movement of said carrier relatively to said fulcrum pin, to cause the levers to become disengaged from the rope.

3. In a load carrier of the type herein referred to for an aerial ropeway, rope gripping mechanism comprising a pair of gripping levers the lower ends of which are adapted to grip an aerial rope between them and edge portions of which above said lower ends are formed with oppositely inclined edge surfaces, a fulcrum pin for said levers free to move in a vertical direction relatively to the carrier, means on said carrier adapted, on downward movement thereof relatively to said fulcrum pin to act 20 against the opposite inclined surfaces on the levers and cause the levers to grip a rope, and abutment means mounted on said carrier, adapted, upon upward movement of the carrier relatively to said fulcrum pin, to act against and cause the levers to become disengaged from the rope.

4. In a load carrier of the type herein referred to for an aerial ropeway, rope gripping mechanism comprising a pair of gripping levers the lower ends of which are adapted to grip an aerial rope between them and the adjacent inner edge portions of which above said lower ends are inclined in opposite directions to one another, a fulcrum pin for said levers free to move in a vertical direction relatively to said carrier antifriction roller means on said carrier, adapted on downward movement of said carrier relatively to said fulcrum pin, to pass 45 between and act against the adjacent oppositely inclined edge portions of said levers and cause the lower ends of said levers to move into their operative positions to grip a rope between them and means adapted, 50 on upward movement of said carrier relatively to said fulcrum pin to cause the levers to move into their open and inoperative position to release a rope from between them.

5. In a load carrier of the type herein referred to for an aerial ropeway, rope gripping mechanism comprising a pair of gripping levers the lower ends of which are adapted to grip an aerial rope between them and the adjacent inner edge portions of 65 which above said lower ends are inclined in

opposite directions to one another, a fulcrum pin for said levers free to move in a vertical direction relatively to said carrier antifriction roller means on said carrier, adapted on downward movement of said carrier relatively to said fulcrum pin, to pass 70 between and act against the adjacent oppositely inclined edge portions of said levers and cause the lower ends of said levers to move into their operative positions to grip a rope between them and abutment means mounted on said carrier, adapted, upon upward movement of the carrier relatively to said fulcrum pin to act against and cause 75 the levers to become disengaged from the rope.

6. In a load carrier of the type herein referred to for an aerial ropeway, rope gripping mechanism comprising a pair of gripping levers a fulcrum pin for said levers 80 free to move in a vertical direction relatively to said carrier, said levers having adjacent gripping jaws below said fulcrum pin and adjacent oppositely inclined edge portions above said fulcrum pin the upper parts 85 of the opposite inclined edge portions forming an obtuse angle between them and the lower part of such adjacent edge portions forming a vertical acute angular space between them, antifriction roller means 90 mounted on said carrier and adapted, on downward movement thereof relatively to said fulcrum pin, to act first against said oppositely inclined upper parts of the inclined edge portions of the lever and move 100 them apart so as to cause the lower ends of the levers to move into their closed positions and then to enter the vertical acute angular space between the edge portions of the lever and cause the gripping levers to 105 grip a rope, and means adapted, upon upward movement thereof relatively to said fulcrum pin to move the levers into their open and inoperative positions.

7. In a load carrier of the type herein referred to for an aerial ropeway, rope gripping mechanism comprising a pair of gripping levers a fulcrum pin for said levers free to move in a vertical direction relatively to said carrier, said levers having adjacent gripping jaws below said fulcrum pin and adjacent oppositely inclined edge portions above said fulcrum pin the upper parts 110 of the opposite inclined edge portions forming an obtuse angle between them and the lower part of such adjacent edge portions forming a vertical acute angular space between them, antifriction roller means mounted on said carrier and adapted, on downward movement thereof relatively to said fulcrum pin, to act first against said oppositely inclined upper parts of the inclined edge portions of the lever and move 115 them apart so as to cause the lower ends of the levers to move into their closed positions and then to enter the vertical acute angular space between the edge portions of the lever and cause the gripping levers to 120 grip a rope, and means adapted, upon upward movement thereof relatively to said fulcrum pin to move the levers into their open and inoperative positions.

125

tions and then to enter the vertical acute angular space between the edge portions of the lever and cause the gripping levers to grip a rope and abutment means mounted 5 on said carrier, adapted, upon upward movement of the carrier relatively to said fulcrum pin, to act against and cause the levers to become disengaged from the rope.

8. In a load carrier of the type herein referred to for an aerial ropeway, rope gripping mechanism comprising a pair of gripping levers, a fulcrum pin for said levers mounted with its axes in a longitudinal vertical plane capable of moving in a vertical direction relatively to said carrier and of oscillating in a longitudinal vertical plane said levers having lower jaws adapted to grip a rope between them and upper oppositely inclined edge surfaces, means on 15 said carrier adapted, on downward movement thereof relatively to said fulcrum pin to act between and against the oppositely inclined edge surfaces of the levers and cause the levers to move into their closed 20 and operative positions and abutment means on said carrier adapted, upon upward movement of said carrier relatively to said fulcrum pin to act against outer edge surfaces of the levers and cause the levers to move 25 into their open and inoperative positions.

9. In a load carrier of the type herein referred to, for an aerial ropeway, rope gripping mechanism comprising a pair of gripping levers, a fulcrum pin for said levers mounted with its axes in a longitudinal vertical plane and capable of moving in a vertical direction relatively to said carrier a box like part mounted to oscillate in a longitudinal direction on said carrier and supporting said fulcrum pin, said levers having lower gripping jaws adapted to grip a rope between them and upper oppositely inclined adjacent edge surfaces arranged to form between their upper portions an obtuse 40 angle and between their lower portions an acute angle, antifriction roller means on said carrier adapted on downward movement of the carrier relatively to the fulcrum pin, to first act against the upper portions of the 45 50 oppositely inclined edge surfaces of the

levers to move the levers into their closed position and then to act against the lower oppositely inclined surfaces of the levers to cause the levers to grip a rope between their lower ends or jaws and abutment means on the carrier adapted, on upward movement of the carrier relatively to the fulcrum pin, to act against external edge surfaces of the levers and move the levers into their open and inoperative positions. 55 60

10. For an aerial ropeway, a load carrier comprising a pair of longitudinal parallel members one of which is provided with a box like part and the other of which is provided with bearings for a load hanger, transverse spindles connecting said longitudinal members, sheaves mounted on said spindles, a secondary box like part arranged outside of and adapted to move vertically in relation to the first mentioned or inner box like 65 70 part and provided with lower bearings, a spindle carried by the inner boxlike part and extending into vertical slots in the outer boxlike part, a fulcrum pin mounted in said bearings and extending transversely below 75 the inner box like part, a pair of gripping levers mounted on said fulcrum pin and having their upper ends extending into the inner box like part and formed with oppositely inclined edge surfaces, the upper portions 80 of the respective surfaces forming an obtuse angular space between them and the lower portions of said surfaces forming between them an acute angular space, a longitudinally arranged pin carried by the inner boxlike part, antifriction rollers carried by said pin and adapted to act against the inner oppositely inclined edge surfaces of the levers to move the levers into their closed operative 85 90 positions when the carrier is moved upward relatively to the fulcrum pin and longitudinally arranged pins carried by the inner box-like part and adapted to act against the outer edges of the levers and move the levers into their open and inoperative positions. 95

Signed at London, England, this 12th day of May, 1922.

LUCY JANE ROE,
Executrix of said John Pearce Roe, deceased.
